INVENTOR:
Joseph W. Pearl,
BY
Horace Barnes,
ATTORNEY.

UNITED STATES PATENT OFFICE.

JOSEPH W. PEARL, OF KELSO, WASHINGTON, ASSIGNOR OF ONE-HALF TO JOHN F. BURCH, OF KELSO, WASHINGTON.

FOLDING SQUARE.

Application filed July 21, 1924. Serial No. 727,227.

To all whom it may concern:

Be it known that I, JOSEPH W. PEARL, a citizen of the United States, residing at Kelso, in the county of Cowlitz and State of Washington, have invented certain new and useful Improvements in Folding Squares, of which the following is a specification.

This invention relates to improvements in squares of the folding type, and particularly to squares that are adjustable to various angular positions.

The object of my invention is the provision of a square of improved and simplified construction over that type of square shown and described in my prior United States patent numbered 1,161,961, issued November 30, 1915.

A further object of my invention is to provide a square simple and convenient in use wherein a relatively movable blade-member may be quickly and readily closed or opened and set at various predetermined angles without manipulation of the retaining devices.

A still further object of my invention is the provision of novel and automatically operating retaining-devices set flush with or below the plane sides of the blade-members to releasably secure them at various adjusted positions, consisting in a spring-catch yieldingly mounted upon one of said members and co-operating with suitably spaced notches in the other member whereby the parts may be accurately and securely positioned in their adjusted, angular relations.

Other objects and advantages and objects relating to details of construction and arrangement of parts will be readily apparent in the detailed description to follow.

In the accompanying drawings, the views illustrate by way of example an embodiment of my invention, in which:

Figure 1 is a plan view of a square embodying my invention shown in folded condition.

Fig. 2 is a similar view of the invention shown in fully open condition.

Fig. 3 is an enlarged view in cross-section on line 3—3 of Fig. 2.

Fig. 4 is a fragmentary plan view of one of the blade-elements of the invention, detached.

Fig. 5 is a view similar to Fig. 4 of the

complementary blade-element of the invention.

Referring to said views, the reference numeral 1 indicates one of the blade-members of my improved square and 2 the complementary blade-member which are hingedly secured together by a pivot-pin 3 flush with the plane sides of the square at each of its ends. Said blades may be made of metal, celluloid or other suitable material and are of flat rectangular configuration. The blade 1 is formed at one end with a projection 4 extending beyond the inner straight edge 5 of the blade and is formed with a circular beveled margin 6 concentric with said pivot 3 and with a straight margin 7 at right angles to said edge 5. A circular recess 8 also concentric with said pivot is formed on one side of said blade 1 and is undercut at 9 to provide a dovetail groove. Said recess extends into said blade to approximately one-half of the thickness of the blade and includes the projection 4 which is thus one-half of the thickness of the major portion of the blade. A shoulder 10 is formed at the base of said projection 4 at approximately one-half the distance between the outer edge 11 of the blade 1 and a line extended from the said inner edge 5.

The other blade 2 is formed with a projection 12 of circular configuration upon its outer margin 13 which is beveled to interfit within the recess 8 and dovetail 9 of the other member and having said pivot 3 as its center. Blade 2 has a straight portion 15 disposed at right angles to its inner straight edge 16 and is formed with a shoulder 17 adapted to engage the shoulder 10 when the blades are in their furthest extended or right-angled positions. Said blade 2 is circularly recessed at 18 about said pivot to about one-half the thickness of the blade and including the projection 12, the circular margin 20 of said recess 18 is undercut to afford a dovetail groove to slidably receive the beveled edge 6 of said projection 4.

Thus when assembled in the manner shown each said member includes a recess with a dovetailed circular margin and an opposite beveled projection adapted to slidably fit within the recess of the opposite blade. The shoulder 17 of the blade 2 is positioned approximately at one-half the

distance between the edge 15 of the projection 12 and the outermost edge of said projection so that when folded the outer end 21 of the projection 4 will still be retained in the dovetailed margin 20 of the recess 18 giving strength and solidity to the instrument when in folded condition.

A longitudinally extending slot 22 is formed in said blade 1 having its outer end 10 opening into the recess 8, said slot being about the depth of said recess. A spring-dog 23 is rigidly secured at one end 25 in said slot and is formed at its opposite end in an angular head 26 yieldingly extending 15 into the recess 8. Said projection 12 of the blade 2 is formed with a plurality of angular notches 27 corresponding in shape with the head 26 of the spring-dog and respectively positioned about the circular edge 13 20 of the projection in position with respect to the head 26 corresponding to the desired angles at which the blade 2 is to be set relative to the blade 1. Also a notch 28 is positioned at a point in the periphery of said 25 projection 12 corresponding to the position that the head 26 will occupy relative to said projection when the blades are folded so that the blades will be reliably held together when they are inoperative as a square.

30 It will be seen that the invention provides a very convenient and serviceable instrument for all classes of mechanics employing squares of this character where various angular measurements are to be taken. No 35 projections extend from the plane faces of the blades and no other manipulations are required to change the angles between the blades than simply separating or closing the blades more or less with the hands as the 40 head 26 of the dog will readily release from the respective notches and enter the desired notch by a mild pressure exerted on the ends of the blades by the operator.

While I have described my invention with 45 considerable detail it will be seen to be very simple in construction and practicable in use. I wish it to be understood that I am aware of the fact that minor changes may be made by those skilled in the art without departing from the spirit of the invention as indicated by the appended claims:

50 1. A folding square, formed of two blades pivoted together each said blade having a recess formed in its side and a projection slidably engaged in the recess of the complementary blade, each said projection having a circular margin and an oppositely disposed straight edge at right angles to the lateral edges of the respective blade, said circular

margin being received in a groove in the 60 respective recess, a shoulder formed upon one of said blades midway between its lateral edges, and a shoulder formed upon the other said blade adapted to engage said first named shoulder when fully opened and 65 extending midway between the said straight edge of its projection and the curved extremity of said projection.

2. A folding square formed of two blades pivoted together, each said blade having a 70 recess formed in its side and a projection having a beveled edge interfitting in a groove in said recesses, respectively, each said projection having a straight edge at right angles to the lateral edges of the blade, 75 a shoulder formed upon one of said blades midway between its lateral edges, and a shoulder upon the other of said blades extending beyond the projection in the first-named blade when the blades are in folded 80 condition.

3. A folding square formed of two blades pivoted together, each blade having a recess formed in its side and a projection engaged in the recess of the complementary blade, 85 each said projection having a circular margin and an oppositely disposed straight edge at right angles to the respective blade, one of said projections having spaced notches formed in its periphery, a spring-dog mounted in the other of said blades adapted to engage said notches, respectively, a shoulder formed on one of said blades midway between its lateral edges, and a shoulder formed on the other of said blades adapted 90 to engage said first named shoulder when the square is fully opened and extending midway between the said straight edge of the projection of said blade and the curved extremity of said projection.

4. A folding square formed of two blades pivoted together, each said blade having a grooved recess formed in its side and a projection having a beveled edge interfitting in the grooved recess of the other blade, each 105 said projection having a straight edge at right angles to the lateral edges of the blade, a shoulder formed upon one of said blades midway between its lateral edges, a shoulder upon the other of said blades arranged to engage the first named shoulder as a stop when the blades are in right-angular position, one of said projections having spaced notches formed in its periphery, and a spring-dog mounted on the other of said 110 blades adapted to engage in said notches, respectively.

JOSEPH W. PEARL.
